UNITED STATES PATENT OFFICE.

BARTON P. JENKS, OF BOSTON, MASSACHUSETTS.

DESIGN FOR AN ORNAMENTAL BORDER FOR GLASS OR SILVER WARE.

SPECIFICATION forming part of **Design No. 29,787**, dated **December 13, 1898.**

Application filed September 1, 1898. Serial No. 690,048. Term of patent 3½ years.

To all whom it may concern:

Be it known that I, BARTON P. JENKS, a citizen of the United States, residing at Boston, in the county of Suffolk and State of Massachusetts, have invented and produced a new and original Design for Ornamental Borders for Glass or Silver Ware, of which the following is a specification.

In the accompanying drawings, Figure 1 shows an ornamental border made in accordance with my design. Fig. 2 shows an end view of the border illustrated in Fig. 1.

My border consists of two beaded rods or wires 2 2, joined at intervals by rosettes 3. The beaded rods 2 2 are each composed of a series of elongated beads 4, each pair of which is separated by two short beads 5, and the rosettes are each composed of a raised central portion 6, surrounded by a number of radiating depressions 7, arranged in pairs, giving the rosette a scalloped appearance. The outer edge of the rosette is slightly raised, forming a nar-

row rim 8, which follows the scalloped contour of the depressions 7. These rosettes are of substantially the same average thickness as the beaded rods 2, which latter are cylindrical, the essential feature of my design being the two beaded rods joined at intervals by the rosettes 3. The backs of said rosettes are unornamented.

My border is more particularly intended to be made of silver and applied to silverware, glassware, and the like.

I claim—

The design for an ornamental border for glass and silver ware herein shown and described.

In testimony whereof I have hereunto subscribed my name this 18th day of August, 1898.

BARTON P. JENKS.
